UNITED STATES PATENT OFFICE.

ARTHUR SELIGMANN, OF BREMEN, GERMANY.

APPARATUS FOR DRYING AND COOLING GASES PREFERABLY FOR THE PURPOSE OF LIQUEFACTION OF GAS.

Application filed February 21, 1924, Serial No. 694,274, and in Germany May 20, 1922.

For many purposes it is necessary to free gases from aqueous vapor or other easily condensing constituents (for instance benzole). Especially those gases, for instance 5 air, which have to be submitted to the liquefaction must be previously carefully dried as otherwise the vapor contained in the same deposits in the liquefying apparatus as ice, blocks this apparatus and impedes 10 the heat transmission.

To make the drying effective it is necessary to cool the gas to a temperature below the freezing temperature of the easily condensable constituent (for the separation of 15 aqueous vapor, for instance to below 0°). All gas cooling apparatus of known construction possess however the inconvenience that they freeze and must be thawed to make them ready for use. The reason therefore is 20 that in the apparatus of commonly used construction the gas to be dried is admitted at the top and delivered at the lower end.

The accompanying drawings show diagrammatically heat exchanger apparatus, 25 Fig. 1 being a diagrammatical illustration of a refrigerating device, and Fig. 2 showing diagrammatically a refrigerating device combined with a separation device.

In Fig. 1 of the drawings a refrigerator according to the invention is diagrammatically shown. The refrigerating medium flows in the direction of the arrows *e e*. The gas to be cooled enters at *f*, moves in 30 the direction of the arrows *g* and flows out at *h*. The condensed liquid can be withdrawn at *k*.

If, for instance the saturated air contains at 20° C. in 1 c. m. 17.3 grams of vapor it contains at 0° C. only 4.8 grams, wherefrom 40 it follows that at the cooling up to 0° 72% of the moisture contained in the air has condensed, and according to my invention this 72% of condensed liquid can flow back to the hotter zones to be continuously or 45 intermittently withdrawn. Only the remaining 28% will settle as solid deposit and give cause for blocking of the refrigerator by ice so that the refrigerators constructed according to the present invention call for 50 the thawing out operation with one-fourth of the frequency only at which the refrigerators of known construction have to be thawed out.

55 A further characteristic feature of the invention consists in the arrangement of the

counter current heat exchanger of the gas liquefying and separating apparatus in the above stated manner. Such an arrangement is diagrammatically shown in Fig. 2 of the drawings. As shown in this Fig. 2, 60 the counter current heat exchanging apparatus *l* is associated with a separation device or column *m*, valves being interposed in the conduits through which air to be separated in its constituents is caused to flow through 65 the heat exchange apparatus and separation device.

According to the present invention the flow of the gas to be liquefied which comes from the compressor is directed from below 70 upward. If after a longer time of working the apparatus has frozen and must be thawed the liquid will flow back into the hotter zones, whereby the thawing is considerably accelerated. The entire liquefaction and separation plant is preferably 75 built in such a manner that the warm gas used for thawing flows only through the counter current heat exchanger *l* without 80 getting into the separation device (column) *m*. In this case the column may remain cold and it is only necessary to moderately heat the counter current heat exchanger *l* so 85 that the plant is re-started much more rapidly than otherwise.

In the operation of the device diagrammatically illustrated in Fig. 2, air at high pressure is conveyed into the conduit *s*,—the valve *n* being open, and flowing through the refrigerating apparatus *l*, it continues through the conduit *t* into the pipe coil located as shown at the bottom of the column *m*, and the valve *q* being open it is 90 discharged into the separation device or column *m*. The separation takes place, the nitrogen being discharged, while the valve *r* is closed, thru the counter current heat exchanger *l* and leaving at the conduit *u* of 95 said heat exchanging apparatus as the valve *p* is opened.

When it is desired to thaw out the refrigerating or heat exchanging device *l*, the valve *p* is opened; and air preferably coming from the compressor enters the conduit *u*, rises after having passed thru the opened valve *p*, into the heat exchange apparatus, and is discharged through the conduit *v*, as 100 now the valve *r* is opened. All of the other valves are closed and the air for thawing 105 out the refrigerating device, therefore, does 110

not pass through the other conduits or the column.

For one column several counter current heat exchangers may evidently be provided so that no interruption of service can occur. For the thawing hot gas from the compressor is preferably used which is in this case not conducted into the water cooler, its heat of compression being utilized for the

10 thawing.

What I claim is:

In an apparatus for the liquefaction and separation of gases, a countercurrent heat exchanger having at its lower end a valved 15 inlet for high pressure gas, a conduit extending upward from the valved inlet in the interior of the heat exchanger and hav-

ing an outlet at the upper end, an inlet for low pressure gas at the upper end of the heat exchanger, a valved outlet for the low 20 pressure gas at the lower end, and a second valved outlet at the upper end, the valved outlet at the lower end and the second valved outlet at the upper end being in communication with each other through the 25 interior of the heat exchanger, whereby a thawing medium introduced into the heat exchanger at the lower outlet passes through the interior of the heat exchanger in the same direction as the high pressure gas in 30 the conduit.

In testimony whereof, I affix my signature.

ARTHUR SELIGMANN.
